Frank A. Cutler, ATTORNEY.

UNITED STATES PATENT OFFICE.

HOWARD A. SPEAR, OF SPRINGFIELD, MASSACHUSETTS, ASSIGNOR OF ONE-HALF TO
JOHN W. STACY, OF SPRINGFIELD, MASSACHUSETTS.

FLUSHING VALVE.

Application filed August 4, 1923. Serial No. 655,686.

To all whom it may concern:

Be it known that I, HOWARD A. SPEAR, a citizen of the United States of America, and a resident of Springfield, in the county of Hampden and State of Massachusetts, have invented a new and useful Flushing Valve, of which the following is a specification.

My invention relates to improvements in flushometers, and consists generally of a body having therein inlet, outlet, pressure, and relief chambers, said relief chamber communicating with said outlet chamber, a main valve between said inlet and outlet chambers, movable compression means between said outlet and pressure chambers, the same being connected with said valve, a downwardly-opening, spring-pressed relief valve between said pressure and relief chambers, a tubular member extending downwardly from the floor of said relief chamber, through said pressure chamber and the parts and members below the same, into said inlet chamber, a valve-stem extending downwardly from said relief valve and carrying at the lower end, in said tubular member, a dash-pot which serves as a retarding valve, said dash-pot comprising a member which has an interior passage, with a gravity ball-valve to close said passage at the top, means of communication between opposite ends of said dash-pot outside of said passage therein, and mechanical means for opening said relief valve, together with such other parts and members as may be necessary or desirable in order to render the flushometer or flushing valve complete and serviceable in every respect, all as hereinafter set forth.

The primary object of my invention is to produce a flushing valve that is simple in construction and operation and positive in action, consists of few parts which are not liable to get out of order or become inefficient or ineffectual, is comparatively inexpensive in construction, and strong and durable, and wherewith are obtained a quick discharge and a slow closing movement involving a predetermined time interval, the action of the valve being automatic throughout the opening and closing operations, after the initial impetus is given through the medium of a cam, plunger, or other more or less similar device.

Another object is to produce a flushing valve which is non-leakable, free from

water-hammer, and withal highly practicable and efficient.

Many flushing valves heretofore constructed have been of such a complicated nature or character and consisted of such a large number of parts as to render the same unsatisfactory and impracticable in many respects, and one of the most important advantages of the present flushing valve resides in its simplicity of construction.

A further object is to afford means for obtaining ready access to the parts and members contained within the body of the flushing valve, to the end that adjustments, repairs, and replacements of such parts and members, should any be required, can be made easily and quickly, and this without impairing the efficiency of said valve after the same has been restored to its former whole and complete condition.

Other objects and advantages will appear in the course of the following description.

I attain the objects and secure the advantages of my invention by the means illustrated in the accompanying drawings, in which—

Figure 1 is a central, vertical section through a flushing valve which embodies a practical form of my invention, the movable parts being disposed in closed or otherwise normal or initial positions; Fig. 2, a left-hand end elevation of the operating members, shown in the preceding view, for the relief valve; Fig. 3, a central, vertical section through the upper portion of a flushing valve which is equipped with a plunger, instead of rocker members and a cam, for operating or opening the relief valve, and, Fig. 4, a cross section through the central, tubular member and valve-stem therein looking down onto the dash-pot or retarding valve.

Similar reference characters designate similar parts throughout the several views.

The lower part of the body and the main valve elements of this flushometer are generally similar in construction to what is commonly known as the Jenkins valve.

As shown in the drawings, the valve body comprises a casing 1, and a hollow cap or dome 2 secured to said casing by means of a nut 3. A horizontal member or plate 4 is mounted on the upper edge of the casing 1 beneath the lower edge of the dome 2, such plate having on the under side thereof an

110

105

100

annular flange 5 to engage the inside of said casing adjacent to said upper edge of the same for the purpose of centering said plate. A packing-ring 6 is interposed between the upper edge of the casing 1 and the adjacent edge portion of the plate 4, and a packing-ring 7 is interposed between such edge portion of said plate and the bottom edge of the dome 2. The dome 2 is provided at the bottom with an outwardly-extending, annular flange 8 which is engaged by the nut 3 when said nut is screwed down onto the upper portion of the casing 1, such portion being externally screwed to receive said nut. A tight joint is thus formed between the casing and the cap, and means afforded for readily disconnecting and removing said dome from said casing, and restoring and securing in place again said dome.

The casing 1 is designed to be connected with the usual supply and discharge pipes of an ordinary water-supply system, and said casing has therein an inlet chamber 9 and an outlet chamber 10. The chambers 9 and 10 are separated by means of a partition 11 which is provided with a horizontal valve-seat 12. There is a brass-lined pressure chamber 13 in the casing 1 below the dome 2, and a relief chamber 14 in said dome. The plate 4 forms the top of the pressure chamber 13 and the bottom of the relief chamber 14.

A by-pass or passageway between the relief chamber 14 and the outlet chamber 10 is formed by an opening 15 in the plate 4 and a passage 16 in the casing 1 above said outlet chamber, which opening and passage are in alignment, such passageway necessarily extending through the packing-rings 7 and 6. In order to facilitate the alignment of the opening 15 with the passage 16, when the parts are assembled, the flange 5 may be provided with a downwardly-extending pin 17 which extends from the flange 8 through openings in the packing-ring 7, plate 4, and packing-ring 6 into a passage in the casing 1 below. The arrangement is such that the plate 4, when positioned on the casing 1 by the pin 17, is located with the opening 15 directly above the passage 16. The pin 17, furthermore, insures the location of the dome 2 in a predetermined manner such as is necessary in order properly to position the relief-valve, operating members presently to be described.

A tube 18 depends from the plate 4 and is rigidly secured thereto. The bottom of the tube 18, which is located in the inlet chamber 9 near the bottom of the casing 1, is closed by means of a screw-cap 19. In the axial center of the plate 4 is a valve-seat 20, the axis of said valve-seat being in line with the axis of the valve-seat 12, and a line connecting the axial centers of said

valve-seats coincides with the axis of the tube 18. This tube has one or more openings 21 therein a short distance below the plate 4. Communication between the tube 18 and the compression chamber 13 is established through the openings 21. In one side of the tube 18 is a vertical passage or flattened part 22, such part extending from the horizontal plane of the openings 21 downwardly to the bottom of said tube. The passage or flattened part 22 might be omitted in the event the main-valve parts and members herein-after described have a fairly loose fit on the tube 18.

Within the tube 18 is a valve-stem 23 which extends upwardly through the valve-seat 20, and is provided with a downwardly-opening, relief valve 24 for said valve-seat. At the top of the valve-stem 23 is a head 25. A spiral-spring 26 encircles the valve-stem 23 above the valve 24 and between the plate 4 and the head 25, and normally causes said valve-stem to be disposed in its high position with said valve in closed position. A retarding piston 27 is connected with the base of the valve-stem 23 by any suitable means, such as a pair of obliquely-arranged and downwardly-extending arms 28. There is an axial passage 29 through the piston 27, which passage flares at the top to form a seat 30 for a ball-valve 31. The arms 28 are spread sufficiently wide apart at their bases to permit the ball 31 to be raised from its seat. There is in one side of the piston 27 a vertical passage or flattened part, as represented at 32 in Fig. 4, although such passage or flattened part might be omitted in the event said piston have a fairly loose fit in the tube 18. The ball-valve is normally held on the seat 30 by gravity.

Slidably arranged on the tube 15 is a hollow member 33 which serves as a valve-stem for a valve 34. This is the main valve for closing the valve-seat 12. The valve-stem 33 below the valve 34 is tapped into a valve member 35. A sleeve 36, having a top flange 37 and a bottom flange 38, is mounted on the valve-stem 33. The valve-stem 33 has a top flange 39 between which and the flange 37 is a leather washer or cup-packing 40 that tightly fits the walls of the compression chamber 13 in which latter these members move up and down. The flanges 37 and 39 and the cup-packing 40 form a piston-head and the bottom of the chamber 13. The valve 34 is clamped between the flange 38 and the valve member 35, and when in closed position bears on the top of the valve-seat 12, while the upper portion of said valve member at such time fills the opening through said valve-seat. The lower portion of the valve member 35 is frusto-conical in shape, and there is a plurality of grooves 41 in and lengthwise of the

periphery thereof, consequently, when the valve 34 and said member are elevated so that said frusto-conical, grooved part of said member is in the valve-seat 12, water 5 is permitted to flow from the chamber 9, around the aforesaid member and through said grooves, through said valve-seat, into the chamber 10.

The water in the chamber 9 rises through 10 the passage 22 into the pressure chamber 13, passes through the openings 21 into the tube 18 above the retarding piston 27, and through the passage 32 in said piston into the bottom of said tube. Thus the chamber 15 13 and the tube 18 are filled with water, but no water can enter the relief chamber 14 while the valve 24 is closed. The area of the piston-head being greater than that of the valve member 35, the pressure above said 20 piston-head causes the main valve 34 to be retained in closed position on the valve-seat 12, and without relieving such pressure said valve can not be opened.

As one means for opening the relief valve 24, I provide a cam 42, a rock-shaft 43, and an operating lever or arm 44. The rock-shaft 43 is journaled in a suitable bearing 45 in one side of the dome 2, and the cam 42 and the arm 44 are secured respectively to 25 the inner and outer ends of said rock-shaft, the latter being a horizontal member. The rock-shaft 43 is held against endwise movement by means of a collar 46 secured to said rock-shaft outside of the bearing 45, and 30 a pin 47 projecting from said rock-shaft inside of said bearing. A horizontal stop pin 48 extends inwardly from the bearing 45 into the path of the pin 47, and limits the movement of the rock-shaft 43 in one direction. The rock-shaft 43 positions the cam 42 directly above the valve-stem head 25, and a spiral-spring 49 is arranged to retain 35 said cam, through the medium of said rock-shaft, with the low part of the cam out of contact with or remote from the head 25. The spiral-spring 49 encircles the rock-shaft 43 and has one end secured to the pin 48 and the other end secured to said rock-shaft, and said spring normally retains the pin 47 40 in contact with the pin 48, which pin 48 is then behind the pin 47, with the cam 42 in the position relative to the head 25 that has just been explained. When these parts and 45 members are thus disposed the arm 44 extends upwardly and forwardly from the rock-shaft 43.

Upon swinging the arm 44 downwardly, the rock-shaft 43 is actuated against the resiliency of the spring 49, and in the direction to carry the pin 47 away from the pin 48 and the cam 42 into engagement with the head 25. As the arm 44 continues in its downward movement the high part of the cam 42 rides on to the head 25 and forces 50 said head with the valve-stem 23 down-

wardly, against the resiliency of the spring 26. The valve-stem 23 carries downwardly with it the relief valve 24 and the retarding valve 27, thus opening the way from the tube 18, and from the chamber 13 through the 55 openings 21 in said tube, through the valve-seat 20, into the chamber 14. The ball-valve 31 does not materially interfere with the downward movement of the retarding piston 27 through the water in the tube 18, because 60 said ball-valve is unseated by the sudden plunge of said piston so that the passage 29 is open at the upper as well as the lower end. The upward movement, however, of the piston 27 is retarded, because then the ball-valve 31 is firmly seated. Upon the release of the arm 44, the spring 49 immediately actuates the rock-shaft 43 in reverse direction until the pin 47 contacts with and is stopped by the pin 48, and the cam 42 is 65 carried away from the head 25 and into a position above the limit of the upward travel of said head.

Space is left between the head 25 and the cam 42, when said cam is in normal or initial position, in order that the complete closing of the relief valve 24, under the influence of the spring 26, shall not be interfered with by said cam. 70

The dome 2 is arranged in a manner to 75 have the arm 44 disposed in a predetermined position, usually in a forwardly-extending direction, and the pin 17, in fixing the position of said dome when turned about its axis, is an important factor in determining 80 the position of said arm and the other rocker members, and insuring that they always be properly located. 85

The operation of this flushing valve, assuming that the parts and members are disposed as illustrated in Figs. 1 and 2, is as 90 follows:

The handle of the arm 44 is grasped and said arm is swung downwardly to open the relief valve 24, against the resiliency of the 95 springs 49 and 26, and through the medium of the rock-shaft 43 and the cam 42. The arm 44 is released and the spring 49 restores the rocking members to their initial 100 positions again. The downward movement imparted to the head 25 by the cam 42 is also imparted to the valve-stem 23, and the valve, 24 and piston 27. In moving downwardly, the valve 24 opens the valve-seat 20, and water escapes through said valve-seat 105 into the chamber 14. The retarding piston 27 descends so quickly that it momentarily passes away from the ball-valve 31, the passage 29 being of sufficient size to enable said retarding valve to make the quick descent through 110 the water in the tube 18 and leave said ball-valve behind. The ball-valve quickly descends, however, after the descent of the piston 27, and closes the passage 29 at the 115 upper end. Now the piston 27 can ascend, 120

under the influence of the spring 26, only so fast as displacement of the water, with which the tube 18 is always filled, can be effected through the narrow passage 32. The compression chamber 13 is full of water which has entered the same from the inlet chamber 9 through the narrow passage 22, and the tube 18 is also full of water which has entered through the openings 21 therein, as previously stated, and the water from said tube and said compression chamber immediately passes through the valve-seat 20 into the chamber 14, from which latter the water escapes through the passageway (15--16) into the outlet chamber 10. The water at this time passes from the chamber 13 through the openings 21 into the tube 18 and through the valve-seat 20 into the chamber 14. As soon as the cam 43 releases the head 25 to the spring 26, the latter forces the valve-stem 23 and valves carried thereby upwardly, but only so fast as the water in the tube 18 can be displaced through the narrow passage 32, as previously observed, and the relief valve 24 is eventually caused to close the valve-seat 20. The ball-valve 31 is moved upwardly by and with the piston 27, so that the upper end of the passage 29 is closed securely throughout the ascent of said piston. Previous to the closing of the valve 24, and while the water is escaping from the chamber 13 into the chamber 14, the pressure of the water below the valve member 35 causes said member, the valve 34, and the valve-stem 33, with the other parts and members carried thereby, to be raised a sufficient distance to open the way through the valve-seat 12, and permit the water to pass from the chamber 9 through said valve-seat into the chamber 10. The flow of water from the inlet to the outlet chambers continues until the pressure of the water in the chamber 13 is sufficient to force downwardly the piston-head in said last-named chamber and cause the valve 34 to close the valve-seat 12, when the flow of water from said inlet chamber to said outlet chamber is cut off. The grooves 41 in the valve member 35 facilitate both the opening and closing operations of the main valve. The water pressure begins to increase in the chamber 13, to bring about the closing of the valve 34, as soon as the valve 24 is closed, and continues to increase until the balance of pressure changes from the chamber 9 to the chamber 13. The way for the water to pass from the chamber 9 to the chamber 13 is always open through the narrow passage 22. Water enters the chamber 9 under pressure as usual, and the results described above are due to the fact that a certain amount of water entering said chamber rises through the passage 22 into the chamber 13 until the latter is filled and has a pressure therein equal to the pressure in the chamber 9, and to the further fact that the chamber 13 is much larger in diameter than the opening through the valve-seat 12, or the area of the piston-head in the chamber 13 is greater than that of the main valve 34, so that said valve is closed by the time the pressure in the chambers 9 and 13 becomes equal, and seated with a force proportionate to the difference in such area, as is well understood. It naturally follows that the opening of the relief valve 24 enables the pressure in the chamber 13 to be reduced, with the result that the greater pressure of the water in the chamber 9 causes the valve 34 to be opened. As soon as the relief valve is closed, however, the water pressure in the chamber 13 begins to increase, by reason of the entrance into said chamber of the water through the passage 22, and continues to increase until the force of the water above the piston-head in said chamber is greater than that below the valve 34, when the latter is caused to descend onto its seat, as previously explained.

In lieu of the rock-shaft and cam for operating the relief valve 24, a spring-pressed plunger, as 50 in Fig. 3, may be employed. The plunger 50 is a vertical member slidingly arranged in the axial center of the dome 2 directly over the valve-stem head 25, and is normally retained out of contact with said head by means of a spiral-spring 51 which is interposed between the plate 4 and a flange 52 carried by said plunger. The flange 52 is located on the plunger 50 in position to contact with the bottom of a boss or bearing 53 through which the plunger 50 extends and in which it operates, said bearing being an integral part of the dome 2. The flange 52 limits the upward movement of the plunger 50 under the influence of the spring 51, and retains said plunger at the required distance above the head 25. The plunger 50 may be provided on top above the dome 2 with a head 54.

In practice, the hand or foot is applied to the head 54 and the plunger 50 is forced downwardly against the resiliency of the spring 51 and into contact with the head 25, the downward movement of the plunger being sufficient to force downwardly said head and the valve-stem 23 far enough to open the relief valve 24. As soon as the plunger 50 is released, the spring 51 actuates the same upwardly until the flange 52 comes into contact with the boss 53. Otherwise the second flushing valve functions in a manner similar to that of the first.

The plunger 50 is normally retained out of contact with the valve-stem head 25 with which said plunger is associated for the same reason that the cam 42 is normally retained out of contact with the valve-stem head with which said cam is associated.

More or less change in the shape, size,

- all of the parts of this manometer, in addition to those hereinbefore specifically pointed out or referred to, may be made, 5 without departing from the spirit of my invention or exceeding the scope of what is claimed.
- What I claim as my invention, and desire to secure by Letters Patent, is—
1. In a flushing valve, a hollow body having therein inlet, outlet, pressure, and relief chambers, a valve-seat between said inlet and outlet chambers, a valve for such seat, a piston-head in said pressure chamber, a valve-stem member connecting said valve and piston-head, a valve-seat between said pressure and relief chambers, a downwardly-opening valve for said last-named valve-seat, a tube below said last-named valve-seat and extending through said piston-head, said tube being closed at the bottom and opening into said pressure chamber, but there being an open passage between said inlet and pressure chambers, a 10 stem in said tube for said second-named valve, a perforated piston carried by said stem in said tube, a spring arranged normally to force said stem and its valve and piston upwardly, means normally to close the perforation in said perforated piston, the construction providing for a constantly open passage between both ends of said perforated piston, and means to open said second-named valve against the force of said 15 spring.
2. In a flushing valve, a hollow body having therein inlet, outlet, pressure, and relief chambers, a valve-seat between said inlet and outlet chambers, a valve for such seat, a piston-head in said pressure chamber, a valve-stem member connecting said valve and piston-head, a valve-seat between said pressure and relief chambers, a downwardly-opening valve for said last-named valve-seat, a tube below said last-named valve-seat and extending through said piston-head, said tube being closed at the bottom and opening into said pressure chamber, but there being an open passage between said inlet and pressure chambers, a stem in said tube for said second-named valve, a perforated piston carried by said stem in said tube, a spring arranged normally to force said stem and its valve and piston upwardly, means normally to close the perforation in said perforated piston, the construction providing for a constantly open passage between both ends of said perforated piston, and means adapted to be actuated into contact with said valve-stem above said second-named valve to force said stem downwardly against the resiliency of its spring.
3. In a flushing valve, a hollow body having therein inlet, outlet, pressure, and relief chambers, a valve-seat between said inlet and outlet chambers, a valve for such seat, a piston-head in said pressure chamber, a valve-stem member connecting said valve and piston-head, a valve-seat between said pressure and relief chambers, a downwardly-opening valve for said last-named valve-seat, a tube below said last-named valve-seat and extending through said piston-head, said tube being closed at the bottom and opening into said pressure chamber, but there being an open passage between said inlet and pressure chambers, a stem in said tube for said second-named valve, a perforated piston carried by said stem in said tube, a spring arranged normally to force said stem and its valve and piston upwardly, means normally to close the perforation in said perforated piston, the construction providing for a constantly open passage between both ends of said perforated piston, and means to open said second-named valve against the force of its spring.
4. In a flushing valve, a hollow body having therein inlet, outlet, pressure, and relief chambers, a valve-seat between said inlet and outlet chambers, a valve for such seat, a piston-head in said pressure chamber, a valve-stem member connecting said valve and piston-head, a valve-seat between said pressure and relief chambers, a downwardly-opening valve for said last-named valve-seat, a tube below said last-named valve-seat and extending through said piston-head, said tube being closed at the bottom and opening into said pressure chamber, but there being an open passage between said inlet and pressure chambers, a stem in said tube for said second-named valve, a perforated piston carried by said stem in said tube, a spring arranged normally to force said stem and its valve and piston upwardly, means normally to close the perforation in said perforated piston, the construction providing for a constantly open passage between both ends of said perforated piston, and means to open said second-named valve against the force of its spring.
5. In a flushing valve, a hollow body having therein inlet, outlet, pressure, and relief chambers, a valve-seat between said inlet and outlet chambers, a valve for such seat, a piston-head in said pressure chamber, a valve-stem member connecting said valve and piston-head, a valve-seat between said pressure and relief chambers, a downwardly-opening valve for said last-named valve-seat, a tube below said last-named valve-seat and extending through said piston-head, said tube being closed at the bottom and opening into said pressure chamber, but there being an open passage between said inlet and pressure chambers, a stem in said tube for said second-named valve, a perforated piston carried by said stem in said tube, a spring arranged normally to force said stem and its valve and piston upwardly, means normally to close the perforation in said perforated piston, the construction providing for a constantly open passage between both ends of said perforated piston, and means adapted to be actuated into contact with said valve-stem above said second-named valve to force said stem downwardly against the resiliency of its spring.

through said piston head, said base being closed at the bottom and opening into said pressure chamber, but there being an open passage between said inlet and pressure chambers, a stem in said tube for said second-named valve, a perforated piston carried by said stem in said tube, means normally to close the perforation in said perforated piston, the construction providing a constantly open passage between the ends of said perforated piston, a spring normally to force said stem and its valve and piston against the base of said tube, and means 10 for closing the valve in said tube, said valve being an open passage between said pressure chambers, a stem in said tube for said second-named valve, a perforated piston carried by said stem in said tube, a spring arranged normally to force said stem with its valve and piston upwardly, means normally to close the perforation in said perforated piston, the construction providing for a constantly open passage between both ends of said perforated piston, and means to open said second-named valve against the force of its spring. 15

ton upwardly, and means to open said second-named valve against the force of its spring.

15 10. In a flushing valve, a body comprising a casing having therein inlet and outlet chambers with a valve-seat between, a dome, a plate between said casing and dome dividing the space above said valve-seat, in said casing and dome, into a pressure chamber below and a relief chamber above, and means to secure said dome and plate to said casing, a valve for said seat, a piston-head in said pressure chamber, a valve-stem member connecting said valve and piston-head, a valve-seat in said plate, a downwardly-opening valve for said last-named valve-seat, a tube below said last-named valve-seat and extending through said piston-head, said tube being closed at the bottom and opening into said pressure chamber, but there being an open passage between said inlet and pressure chambers, a stem in said tube for said second-named valve, a perforated piston carried by said stem in said tube, a spring arranged normally to force said stem with its valve and piston upwardly, means normally to close the perforation in said perforated piston, the construction providing for a constantly open passage between both ends of said perforated piston, and means to open said second-named valve against the force of its spring.

20 11. In a flushing valve, a body comprising a casing having therein inlet and outlet chambers with a valve-seat between, a dome, a plate between said casing and dome dividing the space above said valve-seat, in said casing and dome, into a pressure chamber below and a relief chamber above, means to locate said dome in a predetermined position circumferentially on said casing, and means to secure said dome and plate to said casing, a piston-head in said pressure chamber, a valve-stem member connecting said valve and piston-head, a valve-seat in said plate, a downwardly-opening valve for said last-named valve-seat, a tube below said last-named valve-seat and extending through said piston-head, said tube being closed at the bottom and opening into said pressure chamber, but there being an open passage between said inlet and pressure chambers, a stem in said tube for said second-named valve, a perforated piston carried by said stem in said tube, a spring arranged normally to force said stem with its valve and piston upwardly, means normally to close the perforation in said perforated piston, the construction providing for a constantly open passage between both ends of said perforated piston, and means to open said second-named valve against the force of its spring.

25 12. In a flushing valve, a body comprising a casing having therein inlet and outlet chambers with a valve-seat between, a dome, a plate between said casing and dome dividing the space above said valve-seat, in said casing and dome, into a pressure chamber below and a relief chamber above, means to locate said dome in a predetermined position circumferentially on said casing, and means to secure said dome and plate to said casing, a piston-head in said pressure chamber, a valve-stem member connecting said valve and piston-head, a valve-seat in said plate, a downwardly-opening valve for said last-named valve-seat, a tube below said last-named valve-seat and extending through said piston-head, said tube being closed at the bottom and opening into said pressure chamber, but there being an open passage between said inlet and pressure chambers, a stem in said tube for said second-named valve, a perforated piston carried by said stem in said tube, a spring arranged normally to force said stem with its valve and piston upwardly, means normally to close the perforation in said perforated piston, the construction providing for a constantly open passage between both ends of said perforated piston, and means to open said second-named valve against the force of its spring.

30 13. In a flushing valve, a body comprising

45 11. In a flushing valve, a body comprising a casing having therein inlet and outlet chambers with a valve-seat between a dome, a plate between said casing and dome dividing the space above said valve-seat, in
50 said casing and dome, into a pressure chamber below and a relief chamber above, said plate and casing having therein an opening and a passage, respectively, which are in alignment and form a passageway from said
55 relief chamber to said outlet chamber, and means to secure said dome and plate to said casing, a valve for said seat, a piston-head in said pressure chamber, a valve-stem member connecting said valve and piston-head, a
60 valve-seat in said plate, a downwardly-opening valve for said last-named valve-seat, a tube below said last-named valve-seat and extending through said piston-head, such tube being closed at the bottom and opening into said pressure chamber, but there being
65 110
115
120

sure chambers, a stem in said tube for said second-named valve, a perforated piston carried by said stem in said tube, a spring arranged normally to force said stem with its valve and piston upwardly, means normally to close the perforation in said perforated piston, the construction providing for a constantly open passage between both ends of said perforated piston, and means to open said second-named valve against the force of its spring.

14. In a flushing valve, a body comprising a casing having therein inlet and outlet chambers with a valve-seat between, a dome, a plate between said casing and dome dividing the space in said casing and dome, above said valve-seat, into a pressure chamber below and a relief chamber above, said plate and casing having therein an opening and a passage, respectively, which form a passageway from said relief chamber to said outlet chamber, means to insure the alignment of said opening with said passage, and to locate said dome in a predetermined position circumferentially on said casing, and means to

5 ranged normally to force said stem with its valve and piston upwardly, means normally to close the perforation in said perforated piston, the construction providing for a constantly open passage between both ends of said perforated piston, and means to open said second-named valve against the force of its spring.

10 piston-head in said pressure chamber, a valve-stem member connecting said valve and piston-head, a valve-seat in said plate, a downwardly-opening valve for said last-named valve-seat, a tube below said last-named valve-seat and extending through said piston-head, said tube being closed at the bottom and opening into said pressure chamber, but there being an open passage between said inlet and pressure chambers, a stem in said tube for said second-named valve, a perforated piston carried by said stem in said tube, a spring arranged normally to force said stem with its valve and piston upwardly, means normally to close the perforation in said perforated piston, the construction providing for a constantly open passage between both ends of said perforated piston, and means to open said second-named valve against the force of its spring.
